UNITED STATES PATENT OFFICE.

CHARLES ENDRES, OF DES MOINES, IOWA.

DESIGN FOR A TRANSMISSION-CASE-SUPPORTING MEMBER.

60,289.

Specification for Design.

Patented Jan. 24, 1922.

Application filed May 31, 1921. Serial No. 473,913. Term of patent 14 years.

To all whom it may concern:

Be it known that I, CHARLES ENDRES, a citizen of the United States of America, residing at Des Moines, in the county of Polk and State of Iowa, have invented a new, original, and ornamental Design for a Transmission-Case-Supporting Member, of which the following is a specification, reference being had to the accompanying drawing, forming part thereof.

Figures 1 and 2 are elevations, at right angles to each other, of a transmission-case supporting member, showing my new design. Figures 3 and 4 are cross-sections on the lines 3—3 and 4—4, respectively, of Figure 2.

I claim:

The ornamental design for a transmission-case supporting member, as shown.

CHARLES ENDRES.
